CLAIM

The ornamental design for a video camera, as shown and described.

DESCRIPTION

The present application is also related to U.S. patent application Ser. No. 29/549,995, filed Dec. 29, 2015, titled “Camera Stand,” now U.S. Pat. No. D802,647, and U.S. patent application Ser. No. 29/549,999, filed on Dec. 29, 2015, titled “Camera Stand,” now U.S. Pat. No. D812,124, each of which is hereby incorporated by reference in their entirety.

FIG. 1 is a front perspective view of a video camera showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict portions of the video camera in which the design is embodied that form no part of the claimed design. The broken lines shown which are immediately adjacent to the shaded areas represent the bounds of the claimed design and form no part of the claimed design.

1 Claim, 3 Drawing Sheets

Related U.S. Application Data

continuation of application No. 29/549,992, filed on Dec. 29, 2015, now Pat. No. Des. 826,306, which is a continuation of application No. 14/701,283, filed on Apr. 30, 2015, now Pat. No. 9,871,953, which is a continuation of application No. 13/604,399, filed on Sep. 5, 2012, now Pat. No. 9,071,740.
